UNITED STATES PATENT OFFICE

MICHAEL M. KLOSSON, OF KENMORE, NEW YORK, ASSIGNOR TO BUFFALO STEAM PUMP COMPANY, OF NORTH TONAWANDA, NEW YORK

DOUBLE SUCTION CENTRIFUGAL PUMP

Application filed January 3, 1930. Serial No. 418,224.

This invention relates to centrifugal pumps.

Pumps embodying this invention are manufactured at present for use in connection with pumping outfits, for example, for mounting on auto chassis, but it will be understood that it is not intended to restrict this invention to such use, since the invention is readily applicable to pumps which are intended to be mounted on any foundation.

The objects of this invention are to provide a double suction centrifugal pump provided with a suction or inlet tube or duct extending toward opposite sides of the pump, so that either or both ends of the tube or duct may be used to conduct liquid to the pump; also to provide a mounting for a pump of this kind by means of which the pump is supported by the inlet pipes or ducts; also to provide a pump of this kind in which the discharge passage extends through, but does not shut off the suction inlet passage of the pump; also to provide a centrifugal pump in which at least a part of the pump housing extends into the suction or inlet duct, to facilitate the delivery of liquid to be pumped to the pump housing; also to provide a centrifugal pump with means of improved construction for preventing the liquid being pumped from passing lengthwise of the shaft to the shaft bearings; also to improve the construction of centrifugal pumps in other respects hereinafter specified.

In the accompanying drawings.

Fig. 1 is a side elevation of a centrifugal pump and the mounting thereof, embodying this invention;

Fig. 2 is a transverse sectional elevation thereof, on line 2—2, Fig. 1.

Fig. 3 is a transverse section thereof, on line 3—3, Fig. 4; and

Fig. 4 is a central sectional elevation of the pump on line 4—4, Fig. 1, on an enlarged scale.

In the drawings a single-stage, double suction centrifugal pump is illustrated, but it will be understood that the invention is equally applicable to a multi-stage or multi-pump.

The particular pump shown in the accompanying drawings and forming one em-

bodiment of this invention, includes an inlet or suction duct or conduit A having at least a part of the housing B of the centrifugal pump arranged within the suction duct and preferably formed integral therewith, this housing including a discharge passage or duct C, which may also be formed integral with the housing and with the suction or inlet passage A. The pump housing shown extends substantially through the middle of the inlet duct A, and in order to allow ample space between the sides of the suction duct and the pump housing and discharge duct, so that the liquid in this suction duct may pass to either side of the discharge passage, the intermediate portion of the duct may be enlarged or bulged out as shown at a, the ends of the duct being of circular cross section. In the particular construction shown, the pump housing is split horizontally, the lower portion D of the housing being arranged exterior to the suction duct A, and having a flange d which may be bolted or otherwise suitably secured to a flange b of that portion of the housing which is formed integral with the suction duct A. A pump housing of other construction may be employed, if desired.

In order to facilitate the mounting of the pump, the suction duct A may be supported on suitable beams or supports E, which may be frame members of a vehicle, or which may be a part of a fixed foundation. The suction duct A may either be elongated so as to rest upon the frame members or supports E, or, as in the construction shown, extensions F and F' of the suction duct A may be provided, these extensions being in the form of tubes having flanges suitably bolted to corresponding flanges at the ends of the suction duct A, or otherwise secured thereto. When this pump is used in connection with fire extinguishing apparatus, the ends of the extensions F and F' of the suction duct are located at opposite sides of the vehicle where they can be readily connected with a source of water supply. It will, of course, be understood that if only one end of the inlet duct is connected with a water supply, the other end will be closed or sealed. The tubular exten-

sions in the construction shown are provided with lugs *f* or other suitable means to facilitate securing the extensions to either the top or bottom faces of the supports or frame members *E*.

5 By means of the arrangement described, it will be obvious that in case it is desired to have the centrifugal pump discharge the liquid downwardly, it is merely necessary to disconnect the suction intake member *A* from the tubular extensions *F* and *F'*, and invert the suction duct *A* together with the pump.

10 The pump itself is shown more in detail in Fig. 4, which shows clearly the two portions *B* and *D* of the housing. This housing encloses the vanes or blades 10 of the impeller *G*, which is suitably secured to a shaft 11 which may be driven in any suitable manner. The impeller is held against lengthwise movement on the shaft 11 by means of sleeves 12 secured on the shaft. The housing has the usual discharge passage or duct 14 into which the vanes or impellers 10 discharge the liquid which is being pumped, and which terminates in the tangential discharge duct *C*. The pump housing is provided with openings 15 at opposite sides of the impeller, so that liquid from the suction intake duct *A* can pass to the impeller from either or both sides thereof through both openings 15. The removable part *D* of the housing is provided with hollow enlarged portions 16, which communicate with the inlet duct *A* and constitute 20 a part thereof and through which liquid to be pumped can pass to the openings 15.

25 The housing is provided at opposite sides with bearing extensions 17 in which suitable sleeve, ball or roller bearings for the pump shaft 11 are arranged, ball bearings 18 being shown in the construction illustrated. These bearing extensions 17 also contain stuffing boxes of any suitable or desired construction for keeping the liquid which is being pumped 30 from reaching the bearings 18, and for keeping lubricant from the bearings from entering the housing of the pump. Since the stuffing box arrangements are the same in both bearing extensions 17, only one of these arrangements will be described.

35 The particular stuffing box or packing arrangement shown includes a flanged disc 20 made of flexible material, such as rubber or leather, and has an inner flange or lip 21 extending toward the impeller of the pump in such a manner that liquid pressure acting on the packing ring 20 will tend to press the inner flange or lip 21 tightly against the sleeve 12, and thus prevent leakage beyond 40 this packing ring. The packing ring is held in its operative position in the bearing extension 17 by means of a metal positioning ring 22, one face of which engages the packing ring 20, and the other face of which engages 45 a radially extending portion of another

similar packing ring 24, also having an inner flange or lip 25 functioning in the same manner as the flange or lip 21 of the packing ring 20. Another similar packing ring 27 is provided outwardly beyond the packing ring 24, 70 and is arranged so that its inner flange or lip extends outwardly away from the impeller to prevent the flow of liquid in a direction toward the impeller, this ring being employed to prevent oil from the bearing 18 from being drawn into the pump housing. Between the two packing rings 24 and 27 is arranged an annular spacing member or drain ring 30, see Fig. 3, which is provided at intervals with radial holes 31, and the portion of the bearing extension in which this drain ring is located is provided with a discharge orifice 32 through which any liquid which may have passed through the several packing rings may be drained. To facilitate the 75 draining of liquid through the orifice 32, the drain ring has inner and outer annular grooves 33 and 34 connecting with the holes 31, so that liquid passing along the sleeve 12 passes into groove 33 and then flows through the holes 31 to the outer groove 34 and thence to the orifice 32. If desired, a drain pipe 35 may be connected with this orifice 32. The 80 several parts of the stuffing box arrangement are secured in place by any suitable means 85 one means as shown being an externally threaded ring 36 engaging a corresponding threaded portion of the bearing extension 17 of the pump.

90 The ball bearings 18 shown have their inner races pressed against the outer ends of the sleeves 12, for example, by means of nuts 37 engaging screw threaded portions of the shaft 11. A cap 38 closes the outer end of one of the bearing projections 17 and a corresponding cap 39, provided with an opening through which the shaft 11 extends, covers the end of the other bearing extension 17.

95 By means of the stuffing box and bearing arrangement described, the bearings are arranged as closely together as is possible, so that the shortest possible distance between each of the bearings is obtained and a correct and true operation of the impeller shaft results. This construction also has the advantage that the bearings can be arranged in the integral extensions 17 of the pump housing or suction inlet so that these bearings can be more readily kept in alignment with the axis of rotation of the pump shaft, and by providing a stuffing box arrangement which positively prevents the liquid being pumped from 100 passing to the bearings, this construction is made possible, so that the use of bearings separated by a space or distance from the pump housing are not necessary. This arrangement is particularly desirable in a portable pump which is subjected to much more jarring and shocks than is a stationary pump.

105 The arrangement described has the advantage 110

tage that a double-suction centrifugal pump may be employed. This type of pump is more efficient than the single suction pumps heretofore used in fire apparatus and similar portable pumps, and also eliminates the end thrust on the shaft, which is present in all single-suction pumps.

5 I claim:

The combination of a substantially straight duct having openings at opposite ends thereof to receive liquid at either or both of said ends of said duct, a centrifugal pump having a portion of its housing arranged within said duct intermediate the ends thereof, to receive liquid from said duct at both sides of said 10 housing, the other portion of said pump housing being secured to said duct at a peripheral portion thereof and extending toward one side thereof and including passages for liquid 15 from said duct to said other portion of the housing, and a discharge passage from said housing extending to the opposite side of said duct.
